UNITED STATES PATENT OFFICE.

HOMER A. HILL, OF WASHINGTON, DISTRICT OF COLUMBIA.

FLYING-MACHINE.

1,330,321.

Specification of Letters Patent. Patented Feb. 10, 1920.

Application filed March 18, 1919. Serial No. 283,815.

To all whom it may concern:

Be it known that I, HOMER A. HILL, a citizen of the United States, residing at Washington, District of Columbia, have invented new and useful Improvements in Flying-Machines, of which the following is a specification.

This invention relates to flying machines of the helicopter type, and one object of the invention is to provide a flying machine of this character having superposed and oppositely rotating sets of lifting and propelling blades, and with which co-operates an aerofoil surface giving increased lifting capacity, the construction being such that the operation of the propeller blades will produce a partial vacuum above the aerofoil surface in such a manner as to materially increase its lifting effect.

20 A further object of the invention is to provide a novel construction and arrangement of oppositely rotating sets of lifting and propelling blades, whereby the negative or vacuum lift will not only be promoted but stability of the craft insured.

30 A still further object of the invention is to provide a novel construction and arrangement of lifting and propelling blades in co-operation with an aerofoil surface whereby both the lifting action of the blades and that of the aerofoil surface will be jointly promoted and increased.

35 The invention consists of the features of construction, combination and arrangement of parts hereinafter fully described and claimed, reference being had to the accompanying drawings, in which:—

40 Figure 1 is a top plan view of a supporting and propelling mechanism embodying my invention.

Fig. 2 is a vertical longitudinal section through the supporting and propelling mechanism and the car attached thereto.

45 In carrying my invention into practice, I provide a car 1 of any suitable form and construction, but preferably of substantially conical form as shown, having a carriage or wheeled supports 2 for supporting the machine when at rest upon the ground and adapting the same to be moved from place to place upon the ground or to run along the surface of the ground under its own power. This car is designed to contain suitable accommodations for the pilot and passengers, if any, the driving motor (not shown), and the required mechanism

for controlling the machine in flight. As shown, the body 1 may have mounted thereon a vertical rudder 3 for steering the machine laterally, which rudder may be operated by any suitable type of operating means.

50 Mounted on the car is a driving shaft 4 constantly rotated in one direction by the motor, which shaft is coupled at its upper end by a universal or gimbal joint 5 with the lower end of a main propeller shaft 6 extending to a predetermined height above the apex of the car. Supported by the shaft 6 is a propelling mechanism generally of inverted frusto-conical form and consisting of two superposed frusto-conical propeller frames, generally indicated at 7 and 8. The upper propeller frame 7 consists of upper and lower frame members each comprising 70 a hub 9, rim 10, and an annular series of spokes or arms 11 rigidly connecting the hub and rim, the upper propeller being completed by an annular series of propelling and sustaining blades or vanes 12 and the lower propeller by an annular series of blades or vanes 13.

55 The blades or vanes 12 and 13 of the two propeller frames 7 and 8 extend around and are secured to the upper and lower rims 10 of the respective frame members, and the blades of each set are of curved or cambered form, having an outer concave surface 14 and an inner convex surface 15, each blade being provided with a leading edge 16 and 90 a trailing edge 17. The leading and trailing edges of the blades are arranged to overlap throughout the series, and the leading edges of the blades of the upper propeller face in one direction, while the leading edges of the blades of the lower propeller face in the opposite direction. As shown by the arrows in Fig. 1, the upper propeller device 7 may be mounted to revolve in a counter-clockwise direction, while the lower propeller device 8 rotates in a clockwise direction, although it is to be understood that the respective propeller devices may be revolved in the relatively opposite directions, that is to say that the upper propeller device may be revolved in a clockwise direction while the lower propeller device is revolved in a counter-clockwise direction.

100 The shaft 6 receives counter-clockwise driving motion from the motor and the hubs 9 of the upper propeller 7 are fixed directly

- to said shaft, and hence the blades 12 are rotated with and in the same direction as the shaft 6, while the lower hub 9 of the lower propeller 8 is fixed to a bevel gear 16 loosely mounted on the shaft 6 and receiving motion from a bevel drive gear 17 fixed to said shaft 6 through the medium of an intermediary gear 18, journaled to rotate upon a sleeve 19 mounted on the shaft 6.
- 10 It will thus be understood that the lower propeller 8 will be revolved in the opposite direction to the propeller 7, and that the blades 13 will accordingly be revolved in the reverse direction to the blades 12, the rotation of the two propellers 7 and 8 in opposite directions tending to keep the ship stable in the air, the side torque or thrust of one propeller being counteracted in a large measure by that of the other propeller.
- 15 Supported beneath the lower end of the lower propeller 8 of the frusto-conical propelling mechanism is an aerofoil 20, comprising a dished circular body having a concave lower face 21 and a convex upper face 22. This aerofoil is supported by a bracket 23 carried by a sleeve 24 loosely mounted on the shaft 6, said sleeve being provided with a crank arm 25 coupled to the upper end of a sustaining and adjusting rod 26 extending downwardly into the car 1. The rod 26 has a threaded lower end engaged by a locking and adjusting screw 27 revolvably mounted between a pair of spaced bracket members 28 within the car, said screw being provided with a hand wheel or other suitable form of operating member whereby the rod 26 may be adjusted upwardly and downwardly, by which means the propelling mechanism as a whole may
- 20 be tilted in a fore-and-aft direction for the purpose of steering the craft vertically and balancing it longitudinally, it being understood that the rod 26 normally holds the bracket 23 in a fixed position and against rotation. By the adjustment of the rod 26, the propelling mechanism may also be suitably inclined at a desired angle of incidence to propel the machine forward at greater or less speed or to vary its climbing angle.
- 25 The joint 5 is adapted to permit of the described tilting of the propelling mechanism, while also permitting driving motion from the shaft 4 to the shaft 6.
- 30 As the propeller blades 12 rotate in one direction, while the propeller blades 13 rotate in the opposite direction, it will be understood that a gyroscopic action is instituted tending to maintain the stability of the craft, while the blades at the same time owing to their angle of incidence continuously compress the air for a supporting action in the rotation of the propellers. In the operation of launching the craft, the propellers, arranged in the normal position
- 35 shown in Fig. 1, are set into action and re-

volved at high speed to lift the craft directly from the ground into the air. When the desired altitude is reached the propellers are then tilted forwardly at such an angle that the propeller blades will exert a supporting effect as well as a propelling effect upon the air to drive the machine forward in course of flight. It is obvious that the propelling and lifting effects may be varied and governed by driving the propellers at different speeds and tilting them to different angles of inclination. By reducing the speed of the propellers to a desired degree, the machine may be maintained at a given altitude in the air and driven forward, and so by proper tilting motions of the propellers in a fore-and-aft direction the longitudinal stability may be maintained, the gyroscopic action of the oppositely rotating sets of propellers giving inherent lateral stability. It will be evident that by proper adjustments of the propellers the craft may be caused to ascend in a direct vertical path or to ascend at an angle, and by reducing the speed of the propellers the craft may be allowed to descend at any desired low rate of speed either in a direct vertical path or at a gliding angle. By also reducing the speed of the propellers to exact sustentation speed, the craft may be made to hover in the air over any given point.

It will be observed that in the action of the propeller blades 12 and 13, the outer or reaction surfaces of said propeller blades, being inclined in the direction of motion, will compress the air for a lifting impulse and then throw off the air to reduce head resistance. It will also be evident that the air entering the space or chamber formed by the frusto-conical propelling device, and bounded by the said blades 12 and 13, will be forced by the inner or rarefaction surfaces of the blades to take a whirling motion or form a vortex, and travel upward out of the open top of said chamber. By this means a partial vacuum will be formed within the chamber to secure an additional negative lift on the blades 12 and 13, and also to secure an increased negative lift on the aerofoil 20. For the purpose of facilitating the discharge of the air from the vacuum chamber, deflectors 29 and 30 are provided which extend radially of the chamber and are arranged in the path of the air to arrest its continuous rotary movement and first deflect it for sustaining compression and then allow it to pass upwardly for escape. These deflectors may be disposed at any suitable position or at any suitable angle for the purpose. The deflector 29 is secured to a sleeve 31 surrounding the shaft 6 and which is provided with a gear 32 meshing with a gear 33 driven from a gear 34 fixed to the shaft, whereby said deflector 29 will revolve in the opposite direc-

tion to the blades 12. The deflector 30 is secured to a sleeve 35 which is fixed to the shaft 6 so that it will revolve in a direction reverse to the direction of the blades 13. 5 Hence the deflectors will operate to facilitate compression as well as the upward travel of the air accumulating in the vacuum chamber, thereby maintaining a continuous partial vacuum in said chamber, 10 with the result of promoting and increasing the lifting forces of the lifting and propelling blades as well as that of the aerofoil 20.

Having thus fully described my invention, I claim:—

- 15 1. A flying machine embodying a car and a supporting surface comprising a frusto-conical body consisting of upper and lower reversely rotatable propellers.
- 20 2. A flying machine embodying a car and a supporting surface consisting of a frusto-conical body forming a vacuum chamber, said body comprising a pair of superposed oppositely rotating propellers, each propeller having a series of blades upon the periphery thereof.
- 25 3. A flying machine embodying a car and a supporting surface of frusto-conical form comprising a pair of superposed oppositely 30 rotating propellers, each propeller comprising a frame having an annular series of propeller blades upon the periphery thereof, said blades inclined to rotate at an angle to the perpendicular, and means for adjusting the propeller body to vary the working angles of the blades.
- 35 4. A flying machine embodying a car, a supporting surface consisting of a frusto-

conical body forming a vacuum chamber, said body comprising a pair of superposed 40 oppositely rotating propellers, and an aerofoil surface above the car and in proximity to the base of said vacuum chamber.

5. A flying machine comprising a car, an aerofoil disposed above the car, and a propelling mechanism comprising a frusto-conical body forming a vacuum chamber disposed above the aerofoil, said body consisting of upper and lower oppositely rotating sets of blades. 50

6. A flying machine embodying a car and a supporting surface comprising a frusto-conical body forming a vacuum chamber, said body consisting of upper and lower oppositely rotating propellers each having a 55 series of propeller blades upon the periphery thereof, and a deflector inclosed by the blades of each propeller and arranged to deflect the air upwardly from the vacuum chamber, each deflector being arranged to rotate in a direction reverse to the direction of rotation of the coöperating propeller blades.

7. A flying machine embodying a car, an aerofoil surface arranged above the car, a 65 propelling mechanism comprising superposed oppositely rotating propellers forming a vacuum chamber arranged above the aerofoil, each propeller comprising an annular frame carrying a peripheral series 70 of blades, and a deflector arranged within each propeller and rotating in the opposite direction to the blades thereof.

In testimony whereof I affix my signature.

HOMER A. HILL.
